UNITED STATES PATENT OFFICE.

DENNIS A. GORMLEY AND DANIEL W. REID, OF ATLANTIC CITY, NEW JERSEY.

CARBURETOR.

Application filed August 16, 1920. Serial No. 404,010.

To all whom it may concern:

Be it known that we, DENNIS A. GORMLEY and DANIEL W. REID, citizens of the United States, and residents of Atlantic City, in the county of Atlantic and State of New Jersey, have invented certain new and useful Improvements in Carburetors, of which the following is a specification.

The invention relates to a carburetor for internal combustion engines.

Among the principal objects are: to dispense with a fuel float chamber adjacent to or combined with the carburetor; to provide fuel supply and control devices which operate satisfactorily without a float chamber; to provide means for regulating the fuel supply and atomizing the fuel in an improved and economical manner; to provide interconnected air control or throttle mechanism and fuel control valve mechanism of a new and improved form; and to improve and simplify the construction of carburetors in other respects.

The characteristics and advantages of the invention are sufficiently further described in the following detail description of the accompanying drawings which show one exemplifying embodiment of the invention. After considering this it will be apparent to persons skilled in the art that many modifications may be made within the principles of the invention, and we contemplate the employment of any structures which are properly within the scope of the appended claims.

In the drawing:

Fig. 1 is a side elevation of a typical internal combustion engine with the carburetor attached.

Fig. 2 is an enlarged side elevation of the carburetor.

Fig. 3 is an end view.

Fig. 4 shows a modified form of our device, with parts broken away to show the interior mechanism.

Fig. 5 is a cross-section of the device shown in Fig. 4 along the line 5—5.

Referring to the drawings, there is shown an internal combustion engine designated by the numeral 1, having an exhaust manifold 2 and an intake manifold 3. Attached to the exhaust manifold is a metal heater box or container 4. This heater box is fastened to the exhaust manifold 2 by means of suitable bolts or rivets 5, and leading to the interior of this box is a pipe 6, which

conducts heated exhaust gases from a point 6' of the exhaust manifold into the interior of the box.

From the gasoline tank, (not shown) there is provided a pipe 7 which leads to the heater box 4, and is bent in convolutions for a portion of its length as designated by the numeral 8 within the heater box. The length of the convolutions 8 and the construction of the heater box are such that the fuel passing through pipe 7 will be thoroughly heated in its passage through the heater box. From the lower end of the heater box 4, the heated fuel passes through a pipe 8' to a mixing chamber 10, which is suitably bolted by bolts 11' to the intake manifold 3. The pipe 8' before its entrance into the mixing chamber 10 has a restricted portion 9, the exit of which has a conical shape into which is adapted to fit the end 10' of a needle valve. Integrally formed with the needle 10' is a washer 11 that precludes the upward movement of the needle beyond a certain predetermined point.

The pipe 8' is provided with an elbow 12' projecting horizontally at a right angle to the pipe, and this elbow is constructed with a collar 12 that serves to attach the pipe to the wall of the mixing chamber 10.

Integrally formed with the elbow 12' is an extension 13 constituting the atomizer proper and projecting at right angles into the mixing chamber 10. This atomizer 13 is hollow and of cylindrical shape, and has a series of relatively small apertures 14, leading from the interior hollow portion to the exterior surface. There is provided a closing member or plug 15 which prevents passage of any gasoline out the end of the atomizer 13. Facing the upward current of air from the chamber 10, there is a large circular aperture 16 cut into the atomizer 13. This large aperture allows free ingress of air to the interior of the atomizer and the air therein mixes with the gasoline and the mixture passes out from the holes 13 and is taken up into the intake manifold 3 of the engine.

Not only is atomizing accomplished by means of the ingress of air through the large aperture 16, but moreover there is an atomizing effect due to the seepage of gasoline through the small holes 14, which gasoline is taken up from the exterior of the atomizer 13, by the current of air passing around the structure.

Constructed integrally with the wall of

the mixing chamber 10 is an extension wall 17 forming the side walls of a housing for a valve controlling structure to be later described. This housing is provided with a 5 cover plate 18 which is detachably secured to the wall 17 of the housing. Attached to the needle valve 10' and preferably formed as an extension of the needle structure is a connecting shaft 19 provided on one face 10 with a rack 20. The shaft 19 is adapted to extend through the upper wall 17 of the housing and out through the lower wall. The housing thus forms a bearing within which the rod 19 reciprocates. The rack 20 is adapted to engage with a gear 21, which rotates on a shaft 21', that is supported in a strip 22' that extends across the interior of the housing. In mesh with the gear 21 is a pinion 22, keyed to a shaft 23, to which 15 is attached a butterfly valve 23', that controls the flow of the air into the mixing chamber 10. This shaft 23 extends to the exterior of the housing and is keyed to an operating link 24, which is manually operable, preferably from the driver's seat in the case of the application of my invention to an automobile. To control the admission of air through the inlet 26' of the mixing chamber, there is provided a second valve 20 26 operated by link 27. This valve is adapted to be set in accordance with the weather and is ordinarily not changed except as the temperature demands it. Attached to the inlet end 26' of the mixing chamber 10 is 30 a metal pipe 28, which for a portion of its length is coiled around the exhaust manifold 2 so that the air sucked through the end 29 of the pipe will be preheated by the hot exhaust gases before its entrance into the mixing chamber.

From the foregoing, it will be seen that we have devised a carburetor in which the gasolene is preheated through the coils 8 of the heating chamber 4, by reason of the fact 45 that the heating chamber 4 is connected by pipe 6 to the interior of the exhaust manifold. The air is preheated by being drawn through a pipe 28 that encircles the exhaust manifold. The heated fuel passes into the atomizer 13 and escapes through holes 14. The upward flow of hot air through aperture 16 and over the atomizer thoroughly 50 atomizes the fuel and forms a suitable mixture. The proportion of gasoline to air is regulated by means of the rack and pinion mechanism previously described. The shaft 55 23 having been rotated by link 24 to admit a certain amount of air through the butterfly valve 23' rotates with it the pinion 22, which in turn rotates the gear 21 and this, by reason of its operative engagement with the rack 20, reciprocates the shaft 19, and controls the position of the needle 10' in the end of the passage 9 of the gasolene 60 intake pipe. Thus the proportion of gaso-

lene to air having once been determined by experiment will remain fixed and the proper mixture will always be obtained. Regulation for the outside temperature is made through regulation of the valve 26, and the proper position of this valve for greatest efficiency having been once determined the operator will seldom have occasion to make readjustment.

Referring to Figs. 4 and 5 which show a 75 modification of our invention, there is shown a split casting 30 bolted together by bolts 30'. This casting is threaded at 31 to permit its being screwed in place on screw threads 32 formed on the end of the mixing chamber 80 10. The mixing chamber 10 in this case is cut off slightly below the atomizer 13. The casting 30 is provided with a cylindrical chamber 33, in which is adapted to reciprocate valve stem 34, which protrudes through 85 the bottom of the casting 30 through a hole therein, as designated by the numeral 34'.

Screw threaded to the upper end of the shaft 34 is a conical valve 35 which is fitted to accurately engage the conical valve seat 90 36 formed in the casting 30. There is provided a key 37 which fits within the casting 30 and has a lug 38 that protrudes into the cylindrical chamber 33. This key 37 fits into a keyway 39' of a rack 39 to which the 95 valve stem 34 is attached. Keyed to a shaft 40 by a key 41' is a gear 41 which meshes with the rack 39. The shaft 40 is adapted to be rotated by means of a link 24. Meshing with the pinion 41 is a rack 42 that fits 100 within a cylindrical passageway of the casting. This rack 42 is attached to the connecting shaft 19 which operates the needle valve. The operation of this modified structure is quite similar to the operation of the 105 first described construction. Upon rotation of the shaft 40, the gear 41 rotates to operate the rack 39, which controls the air inlet valve, and the rack 42, which controls the needle valve admitting the gasolene. This construction has been found to be particularly 110 sturdy and simple to manufacture.

While we have described but two embodiments of our invention, it is apparent that many modifications may be made therein by those skilled in the art without departing from the spirit thereof, and we desire, therefore, that our invention be limited only as set forth in the appended claims or by the showing of the prior art.

We claim:

1. In a carburetor, in combination with a body providing an air passage, and a throttle, a fuel atomizing tube intersecting the air passage and provided with a plurality of small fuel apertures and also provided with a larger air aperture directed against the flow of air in said passage, and means for supplying fuel to the tube at one end,

2. A carburetor comprising a body having 130

an air passage formed with a throttle seat, a throttle valve arranged to cooperate with said seat, a stem for said valve guided for movement in the air passage, a throttle rack member connected to the stem, a fuel valve rack member slidably mounted in the body parallel to said stem, a gear located between the rack members and engaging both of them, a shaft having bearings in the body and carrying said gear and arranged for rotation by the operator, a fuel pipe having

discharge means in the air passage above the throttle, a valve seat controlling flow of fuel to the fuel pipe, and a valve cooperating with the fuel valve seat and connected with 15 said fuel valve rack member.

Signed at Atlantic City, in the county of Atlantic and State of New Jersey, this 9th day of August, A. D. 1920.

DENNIS A. GORMLEY.
DANIEL W. REID.
